UNITED STATES PATENT OFFICE.

HALBERT M. WOOD, OF NASHVILLE, TENNESSEE, ASSIGNOR OF ONE-FOURTH TO STANLEY H. O'CONNOR, ONE-FOURTH TO JAMES A. WILLIAMS, AND ONE-FOURTH TO EDWARD T. LOWE, SR., OF NASHVILLE, TENNESSEE.

GATE.

1,129,938.

Specification of Letters Patent.

Patented Mar. 2, 1915.

Application filed September 17, 1914. Serial No. 862,226.

To all whom it may concern:

Be it known that I, HALBERT M. Wood, a citizen of the United States, residing at Nashville, in the county of Davidson and State of Tennessee, have invented certain new and useful Improvements in Gates, of which the following is a specification, reference being had to the accompanying drawings.

- 10 This invention relates to certain improvements in gates and has relation more particularly to a gate of this general character especially designed and adapted for use in connection with railway crossings; and an 15 object of the invention is to provide a device of this general character having novel and improved means whereby a gate may be caused to assume an operative or inoperative position in an automatic manner.
- 20 It is also an object of the invention to provide a device of this general character having novel and improved means whereby the gate is caused to assume one position under the influence of a fluid, such as air, and 25 whereby the requisite tension for the fluid is created by the rolling stock traveling over the track-way with which the gate is adapted to coat.

Furthermore, it is an object of the invention to provide a device of this general character having novel and improved means whereby an audible signal is caused to sound during the period the gate is changing from one position to another or during such 35 period when the tension of the fluid is in excess of that required for operating the gate.

It is also a further object of my invention to provide a device of this general character 40 having novel and improved means whereby the gate is held in operative or closed position independently of the operating means for the gate and whereby said locking means is maintained inoperative during the period 45 the gate is returning to an inoperative or open position.

The invention consists in the details of construction and in the combination and arrangement of the several parts of my improved gate whereby certain important advantages are attained and the device is rendered simpler, less expensive and otherwise more convenient and advantageous for use,

all as will be hereinafter more fully set forth.

The novel features of the invention will be carefully defined in the appended claims.

In order that my invention may be the better understood I will now proceed to describe the same with reference to the accompanying drawings, wherein—

Figure 1 is a somewhat diagrammatic view illustrating a gate constructed in accordance with an embodiment of my invention; Fig. 2 is a view in perspective of a 65 gate as herein embodied, with the locomotive or the like indicated in fragment; Fig. 3 is a sectional view taken substantially on the line 3—3 of Fig. 1; Fig. 4 is an enlarged fragmentary view, partly in side elevation 70 and partly in section, of certain of the operating means for the gate; Fig. 5 is a view, partly in rear elevation and partly in section, of the device as disclosed in Fig. 4; Fig. 6 is a fragmentary view partly in elevation and partly in section of the mechanism for releasing the rod of the operating cylinder and illustrating certain details not disclosed in Fig. 5; Fig. 7 is a sectional view taken substantially on the line 7—7 of Fig. 80 4; Fig. 8 is a view, partly in elevation and partly in section, of one of the compressors embodied herein; Fig. 9 is a sectional view taken substantially on the line 9—9 of Fig. 8; Fig. 10 is a view in top plan of a protecting casing employed in connection with a compressor; Fig. 11 is an enlarged fragmentary view in perspective of the block 26 employed with the compressor together with its guide-way; Fig. 12 is a detail sectional 90 view illustrating the means whereby the releasing arm is maintained normally in proper position relative to the track-way; and Fig. 13 is an enlarged fragmentary view partly in section of the puppet valve herein 95 included.

As disclosed in the accompanying drawings, R denotes the rails of a conventional track-way, to the bases whereof are suitably secured the bearings 1 in which is rotatably supported the shaft 2 disposed transversely of the track-way and terminating at a predetermined distance at opposite sides thereof, the extremities of said shaft being provided with the crank arms 3 disposed in the same general direction. The free extremi-

ties of the cranks 3 have pivotally engaged therewith the pitmen 4 which in turn are pivotally engaged with the inner extremities of the gate arms or bars 5 of conventional construction and supported for rocking movement by the upper extremities of the standards 6. By this arrangement, it will be readily perceived that the gate arms or bars 5 will be caused to move in unison and in the same direction.

The engagement between one of the arms or bars 5 and its coacting standard is, as herein disclosed, created through the medium of a pivot pin 7 disposed through the upper bifurcated extremity 8 of the standard and through a longitudinally disposed slot 9 produced in the arm or bar. A rod 10 is pivotally engaged with the tail of the bar or arm 5 and operatively engaged with the piston 11 adapted for reciprocating movement within the vertically disposed cylinder 12 operatively supported by the standard 6.

In a manner to be hereinafter set forth, the piston 11 is caused to move upwardly under the tension of a fluid, preferably compressed air, in order to cause the gate bars or arms to assume an operative or horizontal position and as such piston moves upwardly the same is held against retrograde movement under the influence of a spring pressed pawl 14 carried by the adjacent standard 6 and engageable with the rack face 15 produced on the rod 10. Movement to the piston 11 in the opposite direction and in order to move the arms or bars 5 into an inoperative or open position is created through the medium of an expandable member 16, herein disclosed as a coil spring of requisite tension, surrounding the rod 10 and interposed between the piston 11 and the upper head 17 of the cylinder 12.

In communication with the cylinder 12 through the lower head 18 thereof is a pipe line 19 extending a predetermined distance along the track-way and having in communication therewith the compressors C. As each of the compressors C is of identical construction, it is thought that a detailed description of one will suffice for the purposes of disclosure.

As herein embodied, each compressor C comprises an elongated base member 20 suitably anchored to the ties T of the track-way or any other suitable support and positioned in close proximity to the outer side of one of the rails R and suitably connected with such base member is a cylinder 21 in communication with the pipe line 19 through the medium of the branch pipe 22 in which is interposed a check valve 23 of conventional construction and for a purpose which is believed to be self-evident. Mounted for reciprocation within the cylinder 21 is a piston 24 operatively connected with a rod 25

projecting a predetermined distance exteriorly of the cylinder and has its outer extremity operatively engaged with a block 26 mounted for sliding movement within the track-way 27 produced in one end portion of the base plate 20. Interposed between the block 26 and the adjacent head 28 of the cylinder 21 and surrounding the rod 25 is an expandable member 29 herein disclosed as a coil spring which serves to normally hold the piston in retracted adjustment. The upper extremity of the block 26 has pivotally engaged therewith around a horizontal axis a dog 30 normally maintained in vertical position and in engagement with the shoulder or stop 31 of the block through the medium of the retractable member 32 herein set forth as a coil spring anchored at one extremity to the dog and at its opposite extremity to the block, as is believed to be clearly shown in the accompanying drawings. The rolling stock or preferably the locomotive indicated in fragment as at L is provided with a depending member 33 pivotally engaged therewith and maintained in normal vertical position through the medium of the retractable member 34 herein disclosed as a coil spring possessing the requisite tension. The member 33 is adapted to strike the dog 30 and thus under the impact of the train force the piston 24 inwardly and thus cause sufficient compression of air as to result in an upward movement of the rod 10 to impart a downward movement to the gate arms or bars. In practice, it is my purpose to employ a sufficient number of compressors C as to result in causing such gate bars or arms to assume an operative or closed position. I find it of advantage to have this done intermittently so that should any persons or teams be passing over the track-way at the time the first compressor is engaged, they will have ample opportunity to clear the track.

In order to protect the rod 25 from the action of the elements, I find it desirable to inclose the forward end portion of the base plate 20 with the hood or casing 35 having produced in its upper portion the longitudinal slot 36 to permit an unobstructed movement of the block 26, and in order that such slot 36 may be closed during the time the block is in its normal position, I provide the slide 37 secured at one end to the block and having its opposite extremity directed through the guide 38 carried by the casing 35, said slide being of a length substantially equal to the length of the slot and of a width to overlie the marginal portions of the slot in a manner and for a purpose which is believed to be clearly apparent to those skilled in the art to which my present invention appertains.

Rotatably supported by the standard 6 provided with the cylinder 12 is a vertical

shaft 39 provided at its upper extremity with a finger or lip 40 adapted to engage a finger or pin 41 carried by the dog 14 in order to release the dog from the stem 10 in order that the same may return to its normal position under the influence of the expandable member 16. The lower extremity of the shaft 39 is provided with an arm 42 extended toward the track-way and adapted to be engaged by the depending member 33 of the locomotive L or the like whereby it will be perceived that as soon as the locomotive has crossed the road-way, the arms or bars 5 will be permitted to automatically assume an inoperative or vertical position.

To prevent the dog 14 from engaging the ratchet face 15 of the rod 10 during the downward movement of said rod, I find it of advantage to pivotally secure to the upper head 17 of the cylinder 12 the pawl 43 of such a length as to engage the inner edge of the dog 14 when the same is retracted and thus prevent it from coming in contact with the rack face 15. The movement of the pawl 43 into such position relative to the pawl 14 is created, as herein disclosed, through the medium of the retractable member 44, herein disclosed as a coil spring, having one extremity suitably anchored to the pawl and its opposite extremity to the head 17. Projecting upwardly from the pawl 43 is a cam member 45 with which is adapted to engage a projection 46 projecting laterally from the rod 10 at a predetermined point thereon whereby it will be perceived that just before the rod reaches the limit of its downward movement, such projection will engage the cam and move the pawl out of engagement with the dog so that such dog may properly engage the ratchet face.

I also find it of advantage to interpose in the pipe line 19 a puppet valve 47 having in communication therewith a whistle 48. By this arrangement, it will be perceived that upon excess tension within the line 19, the puppet valve will be caused to rise which will result in the sounding of the whistle. The puppet valve is also provided with the restricted openings or vents 49 to permit reduction of the pressure within the cylinder 12 in order to permit an unhampered action of the expandable member 16.

In order that an audible alarm or signal may be sounded during the movement of the gate bars or arms 5, I find it of advantage to operatively support by one of the standards 6 a bell 50 adapted to be operated by the gear train 51, one of said gears being fixed to the pivot 52 between the standard 6 and the co-acting arm or bar 5. I also find it of advantage to have the pivotal connection between the rod 10 and its coacting bar or arm 5 and the adjacent pitman 4 created through the medium of the common pin 53.

In order to maintain the arm 42 normally

in a position to be engaged by the member 33, I provide the shaft 39 with a projection 54 to which is anchored an extremity of a retractable member 55, herein disclosed as a coil spring, the opposite extremity whereof being suitably anchored to the adjacent standard 6. As is believed to be self-evident, the movement imparted to the shaft under the influence of this expandable member 55 is limited by contact of the finger or lip 40 with the finger or pin 41.

From the foregoing description, it is thought to be obvious that a gate constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. In combination with a gate, an operating mechanism therefor comprising a rod operatively engaged therewith, fluid means for imparting movement to the rod in one direction, means for imparting movement to the rod in an opposite direction, means normally in engagement with the rod for holding the same against action under the influence of the second means, means for causing the holding means to become inoperative, and means for maintaining said holding means inoperative until the same has traversed a predetermined distance under the influence of the second named means.

2. In combination with a gate, an operating means therefor comprising a rod operatively engaged with the gate and provided with a rack, a pawl coacting with the rack and normally in engagement therewith, means for adjusting the pawl out of engagement with the rack, automatic means engageable with the pawl when disengaged from the rack for maintaining said pawl in its inoperative position, and means for disengaging said last named means from the pawl upon movement of the rod a predetermined distance in one direction.

3. In combination with a gate, an operating means therefor comprising a rod operatively engaged with the gate and provided with a rack, a pawl coacting with the rack and normally in engagement therewith, means for adjusting the pawl out of engagement with the rack, automatic means engageable with the pawl when disengaged from the rack for maintaining said pawl in its inoperative position, and a spring operated pawl adapted to engage the dog when

the same is disengaged from the rack for holding the dog in inoperative position.

4. In combination with a gate, an operating means therefor comprising a rod operatively engaged with the gate and provided with a rack, a pawl coacting with the rack and normally in engagement therewith, means for adjusting the pawl out of engagement with the rack, automatic means engageable with the pawl when disengaged from the rack for maintaining said pawl in its inoperative position, a spring operated pawl adapted to engage the dog when the same is disengaged from the rack for holding the dog in inoperative position, a cam carried by the pawl, and means carried by the rod coacting with the cam for disengaging the pawl from the dog upon movement of the rod a predetermined distance in one direction.

5. In combination with a gate, an operating means therefor comprising a rod operatively engaged with the gate and provided with a rack, a pawl coacting with the rack and normally in engagement therewith, means for adjusting the pawl out of engagement with the rack, automatic means engageable with the pawl when disengaged from the rack for maintaining said pawl in its inoperative position, a spring operated pawl adapted to engage the dog when the same is disengaged from the rack for holding the dog in inoperative position, and a shaft mounted for axial rotation provided with means for rotating the same and having an extension adapted to engage the pawl.

6. In combination with a gate, an operating means therefor comprising a rod operatively engaged with the gate and provided with a rack, a pawl coacting with the rack and normally in engagement therewith, means for adjusting the pawl out of engagement with the rack, automatic means engageable with the pawl when disengaged from the rack for maintaining said pawl in

its inoperative position, a spring operated pawl adapted to engage the dog when the same is disengaged from the rack for holding the dog in inoperative position, a shaft mounted for axial rotation provided with 50 means for rotating the same and having an extension adapted to engage the pawl, and means for maintaining the extension of the shaft normally in engagement with the pawl.

7. In combination with a gate, an operating mechanism comprising a cylinder, a piston within the cylinder, a rod operatively engaged with the piston and the gate, a pipe line in communication with the cylinder, a compressor in communication with the pipe line, 60 said compressor comprising a cylinder, a piston therein, a stem connected with the piston and projecting exteriorly of the cylinder, a sliding block connected to the projected portion of the stem, and an expandible 65 member interposed between the cylinder and block.

8. In combination with a gate, an operating mechanism comprising a cylinder, a piston within the cylinder, a rod operatively 70 engaged with the piston and the gate, a pipe line in communication with the cylinder, a compressor in communication with the pipe line, said compressor comprising a cylinder, a piston therein, a stem connected with the piston and projecting exteriorly of the cylinder, 75 a sliding block connected to the projected portion of the stem, an expandible member interposed between the cylinder and block, a protecting casing for the projected portion of the stem provided with an elongated slot through which the head projects, and a slide connected with the block and movable therewith and overlying the slot.

In testimony whereof I hereunto affix my 85 signature in the presence of two witnesses.

HALBERT M. WOOD.
